ATTACHMENT FOR BEDS

Charles J. Ewald, Columbus, Ohio

Application September 14, 1933, Serial No. 689,397

1 Claim. (Cl. 5—319)

This invention relates to an attachment for beds and particularly to an attachment capable of use for a variety of purposes.

An object of the invention is to provide an attachment of the character specified which may be readily utilized as a support for the bedclothes, either at the foot or at the side of a bed to hold the bedclothes out of contact with portions of the body of an occupant of the bed.

Another object is to provide an attachment, such as that specified in the object immediately above, which attachment embodies means for clamping the end or an edge of the bedclothes in position, thus preventing the same from being pulled out and also facilitating the making of the bed as the bedclothes may be thrown back from off the bed without pulling the same from beneath the mattress.

A further object is to provide an attachment such as that enumerated in the above objects which will not affect the appearance of the bed when it is made up and is not occupied but which attachment can be quickly rendered operative for the purposes specified when the bed is occupied.

A still further object is to provide an attachment of this character which embodies supporting means for the bedclothes, which means is arranged in an inoperative position when the bed is not in use, but can be quickly moved and secured in an operative position by the occupant of the bed.

Another object is to provide an apparatus such as that above specified which will automatically adjust itself to the exact thickness of the mattress and which is simple in construction and can be inexpensively manufactured.

A still further object is to provide an attachment for beds whereby a bed table or a book rack may be easily, quickly and firmly mounted in position across the bed.

Further and additional objects not specifically enumerated above will become apparent hereinafter during the detailed description which is to follow of several embodiments of the invention, such embodiments being illustrated in the accompanying drawing wherein:

Figure 1 is a perspective view of the attachment arranged in position at the foot of a bed or mattress and adapted for supporting the bedclothes in raised position, the attachment being shown in full lines with the bedclothing supporting member thereof resting upon the lower sheet of the bedclothing, while the mattress, together with the clothing supporting member of the attachment

when in raised position, are shown in dot and dash lines;

Fig. 2 is a fragmentary side view of the attachment partly in section and shows the bedclothing supporting member in its inoperative position in full lines and in its operative position in dot and dash lines;

Fig. 3 is a fragmentary perspective view of a somewhat modified form of attachment and illustrates the same as equipped with a bedclothing supporting member especially adapted for supporting the bedclothing along a side edge of the bed;

Fig. 4 is a perspective view illustrating the manner in which the attachment can be utilized to support a bed table;

Fig. 5 is a perspective view illustrating the way in which the attachment may be employed to support a book rack or stand, and

Fig. 6 is a detail sectional view taken substantially on line 6—6 of Fig. 5, looking in the direction of the arrows.

The attachment embodying the present invention is capable of a wide variety of uses for different purposes and, in order to illustrate several of such uses and to disclose the wide range of utility present in the attachment, several of its different uses are illustrated and described herein with the understanding, however, that the invention is not intended to be limited in its utility thereto.

It is often desirable and necessary that bedclothing be supported so as not to contact with the body of an occupant of the bed, as for example, in the case of invalids or persons suffering from injuries of various descriptions. An attachment embodying the present invention which is especially useful in maintaining bedclothing out of contact with the feet of an occupant of a bed has been illustrated in Figs. 1 and 2 of the drawing in a form particularly adaptable for this purpose.

Referring to Fig. 1, the mattress of a bed is diagrammatically illustrated by dot and dash lines and is indicated generally by the numeral 10. The attachment comprises a base portion or member preferably formed of rod stock of suitable size arranged in a substantially U-shaped configuration with legs 11 and a cross portion 12. The legs 11 are connected intermediate their ends by a cross bar or rod 13 which may be welded or otherwise suitably secured at its ends to the legs 11. The free ends of the legs 11 have secured thereto by welding or other suitable means tubes 14 which extend perpendicularly with respect to

the legs 11 and should be of a length substantially corresponding to the thickness of the usual mattress. A pair of clamping members 15 are mounted upon the cross rod 13 intermediate the ends thereof, such members being substantially U-shape and having the ends of their leg portions secured to the rod 13, preferably with one of the members fixedly mounted and the other hingedly mounted on the rod, although both of the members could be hingedly mounted. A loop 16 embraces the members 15 and when moved toward the free ends of the members acts to clamp the same together, it being noted that the legs of the members are bowed so that the loop will engage the same with a clamping action.

The attachment is arranged in position upon the bed by placing the base portion thereof beneath the mattress while the tubes 14 extend vertically toward the top of the mattress and adjacent the foot of the same.

Plugs 17 are slidably mounted in the tubes 14, while a substantially U-shaped member, preferably formed of a single piece of rod stock and indicated at 18, has the free ends of its leg portions pivotally connected to the upper ends of the plugs 17, it being noted that the rod forming the member 18 is of less diameter than the diameter of the plugs, for a purpose later to be explained. In order to brace the upper ends of the tubes 14 a cross rod 19 extends therebetween and has its opposite ends welded or otherwise secured to the tubes at such points.

The lower sheet is arranged on the mattress in the usual manner before positioning the attachment. The plugs 17 are inserted in the tubes 14 and the member 18 thus connected to the base portion, after which the upper sheet and the other bedclothing may be positioned over the attachment and the ends thereof clamped by the members 15 whereupon the foot of the mattress is raised and the attachment is positioned with the base portion thereof engaging the under side of the mattress. When the foot of the mattress is lowered into position the base portion of the attachment will be between the mattress and bed springs, while the bedclothing, already clamped between the members 15, will be drawn into position.

In order to position the member 18 so as to support the bedclothing adjacent the foot of the bed in elevated position and out of contact with the feet of the bed's occupant, it is merely necessary for the occupant of the bed, as he gets into the same, to push upwardly with his feet upon the member 18, whereupon said member swings in a clockwise direction, as viewed in the drawing, until it reaches a vertical position, where, due to gravity and the pressure of the bedclothes thereon, the member 18 and the plugs 17 slide downwardly into the tubes 14 into the position indicated in dot and dash lines in Fig. 1. The member 18 is thus securely held in the vertical or operative position and can not swing further in either direction, because the lower ends of its leg portions extend into the tubes 14, it being noted that the diameter of the rod forming the member 18 is less than the internal diameter of the tubes 14 and the diameter of the plugs 17, so that there will be no possibility of the leg portions of the member 18 failing to drop into the tubes 14.

In Fig. 3 the attachment is illustrated in a slightly different form from that shown in Figs. 1 and 2 and one wherein it is especially adapted to support a member for holding the bedclothes

adjacent a side of the bed out of contact with the body of the bed's occupant.

In this form of the attachment the base member is similar to that previously described and comprises the legs 11, it being noted, however, that a cross rod 20 extends between the free ends of the legs 11 at the lower ends of the tubes 14, such tubes being constructed and secured in position in this instance in the same way as they were in the previously described instance. The cross rod 20 is provided with clamping members 21 similar to the clamping members 15, except that the members 21 extend in a direction parallel with the tubes 14. The base member is positioned beneath the mattress along a side of the bed with the tubes 14 extending upwardly adjacent the outer side of the mattress.

The means for supporting the bedclothing in this instance comprises a substantially U-shaped member 22, preferably formed of a single piece of rod stock with the outer or free ends of its leg portions having angularly disposed parts 23 and 24. The parts 24 will extend into the tubes 14, while the parts 23 extend inwardly and upwardly above the upper surface of the mattress to the point where they merge into the leg portions of the member 22 from whence said member will extend in a substantially horizontal plane transversely of the bed in spaced relation to the top of the mattress. The bedclothing will be supported by the member 22 above the occupant of the bed and at the side of the bed will extend over the parts 23 and downwardly and outwardly of the tubes 14, it being noted that the clamping members 21 can be employed to securely fasten the side edge of the clothing in position. It will be understood that the members 22 may be so proportioned as to extend any desired width transversely of the bed and that such member can be interchangeably used in the attachment with the member 18, previously described. A leg member 22a also preferably formed of rod stock and hingedly connected to the free end of member 22 may be swung downwardly until it rests upon the lower sheet to support the end of the member 22 or the leg 22a may be swung upwardly and backwardly until it rests upon the top of the member 22.

In Fig. 4 the attachment is illustrated as employed for supporting a bed table and it will be understood that the legs 11 of the base portion extend beneath the mattress while the tubes 14 will extend upwardly of the side of the mattress and outside of the bedclothing. The table comprises a supporting frame, preferably formed of a single piece of rod stock, and having straight portions 25 adapted to extend across the bed, which portions are connected at one end by a cross portion 26, while the opposite ends of the portions 25 are turned laterally outwardly, as indicated at 25b, and then perpendicularly downwardly, as indicated at 25a, so as to extend into the tubes 14. When the table is mounted in position upon the bed, the end of the supporting frame opposite to its point of connection with the tubes 14, has secured thereto a leg member 27 which is also preferably formed of similar rod stock and is hingedly connected by suitable means to the supporting frame, although the leg member could be either integral with the frame or fixedly connected thereto. When the supporting frame is positioned across the bed the leg member is of such length that it will engage the top of the bed and sink a short distance into the bedclothing with the result that the supporting frame will be securely held, not only at its point of connection 75

with the tubes 14, but also at its opposite end. In this connection it should be noted that the length of the leg member 27 should be slightly longer than the distance which the perpendicularly turned ends 25a of the portions 25 project above the upper ends of the tubes 14 so as to compensate for the leg member sinking a short distance into the bedclothing.

The table proper, indicated generally at 28, is mounted upon the supporting frame and is preferably formed with flanges or sides 29 along its edges whereby the table is in the nature of a tray. The flanges or sides 29 along the opposite longitudinal sides of the table are provided with grooves 30 which receive the portions 25 and enable the table to be slid into position on the supporting frame from the end thereof having the portions 25b. It will be noted that the table is shown in Fig. 4 with the flanges or sides 29 extending downwardly so that the table presents a plain flat upper surface. When desired the table 28 may be reversed so that the flanges 29 extend upwardly and the table becomes in this instance a bed tray.

In Fig. 5 the attachment is illustrated as supporting a book stand or rack. The base portion of the attachment comprises, as heretofore described, the legs 11 which extend beneath the mattress while the tubes 14 will extend upwardly of the side of the mattress outside of the bedclothing.

The tubes 14 receive the free ends 31 of a suitable length of rod stock having a portion turned at right angles to the ends 31 so as to extend across the bed and formed of convergent lengths 32 connected at their inner ends by a cross-section 33.

A substantially U-shaped member 34 formed of rod stock is secured adjustably to the cross-section 33 by means of a bolt 35 extending through the base of the member 34 and through the section 33, a wing nut 36 being mounted on the bolt to clamp the parts in the desired adjusted position.

The legs of the U-shaped member 34 telescopically extend into the tubular members 37 of a central frame, which members are connected by cross rods 38 extending therebetween with their opposite ends welded or otherwise secured to the tubular members 37. The lower tubular member 37 has welded or otherwise secured thereto substantially at right angles a strip 39 adapted to engage the lower edge of a book.

A second substantially U-shaped member 40 similar to the member 34 has its legs telescopically extending into the tubular members 37 from the ends opposite those which receive the legs of the member 34. A supporting leg 41 preferably formed of rod stock, in the form of a triangle is connected to the lower leg of the member 40 by means of a loop 42 encircling such lower leg, the base of the supporting leg 41 being adapted to rest upon the bedclothing and support the inner end of the book rack or stand.

The members 34 and 40 are provided with pairs of rod loops 43, the loops of each pair being aligned with the loops of the other pair on the opposite member. The loops 43 have their free

ends turned inwardly and brought together and welded or otherwise secured to the base portions of the members 34 and 40 whereby the front and back covers of an open book on the rack may be positioned beneath the loops.

The members 34 and 40 are also each provided with means 44 adapted to engage the pages of an open book on the rack and as illustrated such means may take the form of lengths of suitable rod stock having one of their ends pivotally connected to the members 34 and 40, as by being loosely riveted thereto in the case of the member 40 or by mounting the same upon the bolt 35 in the case of the member 34, whereby the means 44 may be swung upwardly to permit the turning of the leaves and then downwardly to prevent the turning of the leaves.

When it is desired to use the book rack or stand the base portion of the attachment is positioned as heretofore explained and the ends 31 are then inserted in the tubes 14. The wing nut 36 is tightened to hold the book support proper in the approximate position desired, after which the members 34 and 40 are moved inwardly or outwardly with respect to the central frame according to the size of the book which is to be placed thereon. The front and back covers of the book are positioned beneath the loops 43 while the bottom edge of the book engages the strip 39. The book is opened to the desired page and the rods 44 are swung downwardly to hold the pages against turning. The exact position desired for the rack may be obtained by loosening the wing nut 36 and turning the member 34 after which the wing nut 36 is again tightened. When the reader desires to turn a page of the book the rods 44 are swung upwardly to permit the same after which they are again swung into page holding position. It will be understood, of course, that the leg 41 rests upon the bed and imparts stability to the device.

Although specific embodiments of the invention have been illustrated and described herein, it should be understood that the invention is not to be limited thereto but is susceptible of various modifications and adaptations within the scope of the appended claim.

Having thus described my invention, I claim:

A supporting device for bed covers, said device comprising a base section and a cover-supporting section adjustably associated therewith, said base section comprising a U-shaped member horizontally and detachably disposed beneath the mattress of a bed and having its free ends merging into upwardly extending spaced vertical tubular arms, means for maintaining the arms in fixed spaced relation, said cover supporting section comprising a structure of U-shaped configuration having its spaced ends freely slideable in said tubular extending arms respectively, a member slideable in each of the tubular arms, pivot means for connecting the ends of the cover supporting section to the slideable members, said slideable members and arms cooperating to serve as stops and supports to hold the cover supporting section substantially in horizontal position.

CHARLES J. EWALD.
